UNITED STATES PATENT OFFICE.

HAROLD E. AUSTIN, OF LOUISVILLE, KENTUCKY, ASSIGNOR TO AMERICAN CREOSOTING COMPANY, OF LOUISVILLE, KENTUCKY, A CORPORATION OF INDIANA.

MIXING, DISINTEGRATING, OR HOMOGENIZING MACHINE.

Application filed May 18, 1925. Serial No. 31,177.

This invention relates to a mixing, disintegrating, or homogenizing machine in which a surface is revolved in close association with another surface, or in which surfaces are revolved in close association with each other and spaced by a relatively narrow gap through which the liquids must pass.

Heretofore mills have been constructed having closely associated moving surfaces spaced apart by a gap which is of a uniform thickness throughout so that the materials were required to be finely ground before being suspended in a liquid vehicle in order that the particles could be received within the restricted space between the moving surfaces and, furthermore, the viscosity of the liquid not only limited the fineness of the grinding, and the intimacy of the mixture or degree of dispersion of the particles in the liquid, but prevented the admission of the mixture to the relatively narrow space between the moving surfaces.

It is an object of the present invention to provide a mill having a smooth surface of uniform design movable at a high speed relative to another surface and in which the space between the surfaces is so formed that the viscosity of the liquids and the degree of fineness of the grinding of the materials dispersed in the liquid will have no material effect upon the efficient operation of the mill, since compensation for the admission of the liquid has been provided for by the flaring mouth of the receiving end of the space.

A further object of the invention is the provision of a mill having a working surface rotating at a high speed relative to another surface, the surfaces being spaced at progressively varying distances so that the space converges from the flaring feeding end to the discharge end, with compensating means for increasing or diminishing the spacing by an increment which causes the feeding end of the space to be widened a greater extent in proportion to the enlargement of the discharging end. The flaring mouth or feeding end permits the ready admission of a viscous liquid dispersed with particles of a material or a plurality of liquids which are forced through the restricted space and subjected to adhesions, formed and broken at great rapidity and to the action of the centrifugal force so that theoretically the liquid is drawn out into

streams of minute cross-sectional area traveling spirally and acted upon by centrifugal force tending to break said streams into infinitesimal particles and to fling them against the stationary surface. The higher velocities of the surface areas of the rotor due to the increasing diameters of said rotor adjacent the discharging end of the space tends to hasten the discharge of the liquids. However, since the space between the working surfaces converge from the feed to the discharge end and since the width of the discharge end of said space may be regulated at will to compensate for liquids of varying degrees of viscosity and for particles of varying sizes, the rapidity at which the homogenized liquid is expelled may be controlled so that the proper retardation of the liquid in the more or less restricted space between the working surfaces is provided for to give the most efficient results.

The effect of the centrifugal force to produce detached particles and voids is counteracted by a greater mass of the materials being concentrated in the flared mouth of the feeding end of the space where the action of the centrifugal force is at a minimum and where the adhesions are greater so that not only is the feed more uniform than in those machines in which the width of the feeding end between conically formed working surfaces of the space is substantially the same as the width of the discharge end, but a greater quantity of the materials is adhesively picked up and fed between the space thus eliminating any possibility of forming broken films as the final product.

In the drawings,

Figure 1 is an end view of the mill;

Fig. 2 is a vertical sectional view of the mill;

Fig. 3 is a section of the mill showing an enlarged detail of the rotor with the working surface moved into engagement with the fixed complementary surface before adjustment to provide the spacing desired.

Referring more particularly to the drawings, 1 designates a hollow conically shaped casing having cast at its outer end an enlargement 2. The enlargement is provided with an offset annular chamber 3, beyond which is formed a seat 4. To the seat is secured a stator 5 of the mill. The stator is conically shaped and is provided with an

opening 6 at its central portion through which the liquids are admitted either by gravity or under a slight pressure. The lower end of the enlargement 2 is provided with a discharge passage 7 connecting the annular chamber 3 with a discharge pipe 8. The annular lower end of the enlargement adjacent the discharge passage 7 is provided with a base member 9. The standard 10 connects the inner end of the base member with the inner end of the conically shaped casing 1 and together with the base forms a support for the mill which may be secured in any approved manner to a table or other fixed support.

The inner end of the conically shaped casing has a recessed or countersunk portion 11 in which is placed a gasket 12 of any approved design and secured in place by means of threaded bolts 13 and is adapted to seal the chamber 14 in the casing 1 from the chamber 15 formed between the stator 5 and the enlargement 2 on the casing.

A ball bearing 16 is mounted in the upper end of the casing 1 adjacent the packing 12 and abuts at one end a sleeve 17 mounted on a drive shaft 18. The other end of the bearing abuts a hub 19 formed upon the inner end of a rotor 20. The other end of the sleeve is in engagement with a combination thrust and radial bearing generally designated by the numeral 21.

The combination radial and thrust bearing consists of an outer sleeve 22 threaded into the internally threaded portion 23 of the outer end of the casing 1 and has a flange 24 at its lower end on which is seated an outer ball race 25. An inner ball race 26 is adapted to cooperate with the race 25 to maintain the balls 27 in position. The inner race has an intermediate flange 28 provided with a groove adapted to receive the balls 29, while the ring 30, likewise provided with a groove, cooperates with the grooved flange 28 to form a race for the balls 29, the ring 30 being seated upon a shoulder 31 on the outer ball race 25. A ring 32 is bolted to the outer sleeve 21 and engages the upper edge of the outer race 25 and maintains said race in position, while the sleeve 17 embracing the shaft 18 abuts the inner end of the inner race 26. A washer 33 on the shaft 18 and in engagement with the outer end of the inner race 26 is locked in place by a nut 34 screwed upon the threaded portion of the shaft 18. A flanged cap 35 is bolted to the threaded sleeve 21 and has an opening to receive the shaft 18, said opening being sealed by means of a closure 36 bolted to the cap 35 and a felt packing 37 connected with the closure 36. The packing embraces the shaft and aids in preventing the loss of lubricant from the bearing at this point.

The outer annular working face of the stator 5, as shown at 38, is ground to a

curved surface preferably in the shape of a paraboloid or ellipsoid which is adapted to cooperate with a similarly formed surface 39 on the rotor 20. These surfaces are so formed that the mouth or feeding end 40 of the space between the surfaces is wider than the discharge end 41 and the particular construction of the surfaces is such that when the thrust bearing is adjusted so that the rotor 20 will be moved away from the stator 5 the mouth or feeding end of the working space will be enlarged in greater proportion than the discharge end 41 and likewise when the rotor is moved toward the stator the discharge end will be decreased in greater proportion than the decrease in the feeding end of the space between the surfaces 38 and 39. The surfaces are a ground fit as shown in Fig. 3.

A nut 42 is adapted to lock the rotor 20 on the shaft 18. The conically shaped end 43 of the shaft together with a key 45 provides for the rigid locking of the rotor on the shaft without increasing the pressure on the radial bearing 16.

The rotor 20 through the shaft 18 is revolved at a high speed by any convenient means either by direct attachment to a motor or by means of connections with a rotating element as may be desired.

The grinding surfaces are shown as segments of the surface of a hyperboloid of revolution and both of the surfaces are of the same form so that they may be finished during manufacture by grinding one surface against the other. However, it is not essential that the surfaces have the same form since it is only necessary that the space between the surfaces converge in the direction of the flow of the liquid so that liquids of some degree of viscosity impregnated with particles of matter may be readily admitted to the flared mouth of the space and be forced between the surfaces and emerge in a perfectly homogenized state. Other surfaces than a hyperboloid may be employed which will allow the initial grinding of the surfaces against each other and when pulled apart will have the space between the surfaces converging along the line of flow of the liquid, and such surfaces may be that of a torus, a paraboloid of revolution, or an ellipsoid.

In the actual working and manipulation of the mill the clearance between the grinding surfaces is adjusted by the combination radial and thrust bearing to a predetermined point and as may be desired for a particular liquid having a predetermined degree of viscosity and impregnated with particles of a definite size. The shaft is rotated at a high rate of speed as will be the rotor and the materials to be ground emulsified, or intimately mixed, as the case may be, are fed through the openings 6 into the chamber 130

15 where they will be received within the expanded or flared mouth 40 of the space between the surfaces 38 and 39, respectively of the stator and rotor. The materials such 5 as liquids or a liquid having dispersed particles are fed through the inlet 6 under a slight pressure and drawn out through the pipe 8 after passage through the mill. It is not essential that a great pressure be 10 employed for forcing the materials between the rotating disk 20 and its seat 5 since sufficient centrifugal action coupled with adhesions by the cutting of the working face 39 of the disk or rotor at the flared portion 15 of the mouth 40 will be present to accomplish the result and give the mill ample capacity. Due to the high speed, the centrifugal force throws the particles farther in between the converging grinding surfaces 20 which further reduces the size of the particles and this action continues until all the particles are of such fineness that, while being suspended in the liquid, they can pass between the surfaces at their outermost 25 edge where they emerge from the space between the two surfaces. While comparatively coarse particles of the viscous liquids may enter between the surfaces, they cannot proceed until they have been reduced in 30 size or until the liquid has been very finely divided by the action of the mill. It will be appreciated that due to the reduced diameter at the outer end of the rotor 20, as shown at 44, particles which are engaged 35 by this portion of the rotor travel at a slower rate than particles which approach the discharge end 41 of the space between the surfaces 38 and 39, with the velocity increasing as the particles travel from the 40 mouth 40 toward said discharge end so that not only the pressure between the surfaces increases between the mouth and the discharge end, but the materials, whether liquid or particles and liquid, travel at a greater 45 speed up to a predetermined point in the length of the space after which the velocity is retarded by the gradually constricting space adjacent the discharge end.

At the mouth of the space, the liquid is 50 cut by the working surface 39 and is picked up through adhesion to the rotor and the particles dispersed throughout the liquid are forced with the liquid through the gradually converging space and ground to a fineness 55 which is determined by the adjustment of the rotating surface of the disk 20 toward the fixed surface through the longitudinal adjustment of the shaft 18. Since the path of the particles of the materials being treated 60 ed includes a combined forward and circular movement, the result is a spiral feed with a progressively increasing speed until the constriction in the space retards the velocity. The uniform feeding, because of the volume 65 of materials entering the flaring mouth, co-

operates with the acceleration and retardation of the materials to prevent ruptures in the film and provide a uniform discharge.

By the proper selection of the surface used and of the particular portion of the surface used to meet such requirements of the liquid as is governed by the viscosity and size of the particles suspended, the mill may be constructed to meet all the exigencies of grinding or disintegrating the liquid and suspended particles from a comparatively coarse state to a fineness or intimacy not ordinarily contemplated.

While I have shown a mill of the horizontal type, it will be appreciated that a vertical mill may be employed with the same results as have been described in reference to a horizontal mill.

Having thus described the invention, what is claimed:

1. A mixing, disintegrating or homogenizing machine comprising elements rotatable relative to each other and presenting closely adjacent surfaces ground to fit and formed from segments of the surface of a paraboloid of revolution to provide a narrow space therebetween, having a flaring feeding end and a discharge end, said space converging from the feeding to the discharge end, the portion of the space adjacent the discharge end being sufficiently constricted to retard the discharge of material passing through the space, means for rotating one of the elements, and means for increasing the capacity of the feeding and discharge end of the space, the construction of the surface being such that said means will cause proportionately a greater increase in the capacity of the feeding end than the increase in the discharge end.

2. A mixing, disintegrating or homogenizing machine comprising a casing, a cover for the casing, a rotatable disc having a curved working surface, a seat formed on the cover having a working surface complementarily formed to the curved surface of the disc, said working surfaces being ground to fit and formed from segments of the surfaces of a paraboloid of revolution so that when said working surfaces are spaced from each other a gap will be formed between said surfaces converging from end to end to present a flaring feeding end and a restricted discharge end, a drive shaft mounted for rotation in the casing and connected with the disc, means for adjusting the shaft longitudinally of the casing for varying spacing between the working surfaces of the disc and the seat by small increments, the construction of the surfaces being such that the space at the feeding end will be increased in greater proportion to the increase of the space at the restricted discharge end.

3. A mixing, disintegrating or homogenizing machine comprising a casing, a cover for

the casing, a rotatable disc having a curved working surface, a seat formed on the cover having a working surface complementarily formed to the curved surface of the disc, 5 said working surfaces being ground to fit and formed from segments of the surfaces of a paraboloid of revolution so that when said working surfaces are spaced from each other a gap will be formed between said surfaces 10 converging from end to end to present a flaring feeding end and a restricted discharge end, a drive shaft mounted for rotation in

the casing and connected with the disc, and a thrust and roller bearing in the casing and in operative relation with the shaft for adjusting the shaft longitudinally of the casing for varying the shape of the gap, the construction of the surfaces being such that the space at the feeding end will be increased in greater proportion to the increase of the 20 space at the restricted discharge end.

In testimony whereof I affix my signature,

HAROLD E. AUSTIN.
